United States Patent Office.

ANDREW J. WRIGHT, OF CLEVELAND, OHIO.

Letters Patent No. 97,979, dated December 14, 1869.

IMPROVEMENT IN SCAFFOLD FOR GATHERING FRUIT, AND FOR OTHER PURPOSES.

The Schedule referred to in these Letters Patent and making part of the same.

To all whom it may concern:

Be it known that I, ANDREW J. WRIGHT, of Cleveland, in the county of Cuyahoga, and State of Ohio, have invented certain new and useful Improvements in Scaffolds for Gathering Fruit, and other purposes; and I do hereby declare that the following is a full and complete description of the same, reference being had to the accompanying drawings, making part of this specification.

Object.

The nature of my improvement relates to so constructing a portable scaffold, that it may be conveniently moved from one place to another, taken to pieces for easy transportation, for the convenience of taking up but little room when packed away; and, also, the platform or table of said scaffold may be easily raised or lowered to the desired height, and readily secured in place, as will be more fully set forth in the following description thereof.

Drawings.

Figure 1 is a side elevation.

Figure 2, an end elevation.

Figure 3, a top view.

Like letters of reference refer to like parts in the different views.

Specification.

A represents the table or platform, to which is secured the guard B, by means of the posts C extending up from the platform. This guard or rail B is provided with holes, so as to receive the ends of the posts, on which ends are formed tenons, and on the shoulders of which the rail rests, as seen in fig. 1.

The platform or table is mounted upon four or more standards, D, in which is formed a series of notches, E, figs. 1 and 2.

These standards pass through guides F, as seen in fig. 3, said guides being secured to the sides of the platform, or any other desirable place suitable for the purpose.

The standards, when in the slot or opening-guides, receive a part of the same into one of the notches, and, by means of the key G on the opposite side of the notch, which passes into the slot-receiving the standard, firmly holds the standard from slipping or moving back, so that the notch will be out of place in holding up the platform.

By withdrawing the key or wedge, the platform may be raised or lowered to any other notch, according to

the height required for work, and the key G again forced into the slot to hold the notch in place, to support the platform. Thus the platform may be raised or lowered with facility, and secured in the proper position for the work.

On the lower ends of the standards are casters or wheels, so that the scaffold may be readily moved from one tree to another, or from one place to another.

To the sides and ends of the scaffold are attached braces, H I. The side braces H are connected to the standards by means of pins or screws at J, which pass through the ends of said braces into the standards.

The braces I are also secured to the standards, in the same manner, by screws or pins J'. All the pins or screws are made so as to be inserted and withdrawn, as required.

It will be readily seen, that the standards are easily separated from the platform, and, also, from the braces, and the guard around on the platform may also be removed; thus the entire scaffold may be taken to pieces and folded up into a comparatively small bulk for storage or transportation, and again easily put together.

Near the top of each standard is a pulley or roller, as seen at K, fig. 2, over which passes a cord or strap to the eye L, secured to the platform. By this means the platform may be raised and lowered from the ground in a higher position than would be convenient to reach by hand.

The advantages of this scaffold for gathering fruit are obvious, as the fruit may be readily picked without the usual labor of a ladder or climbing, and hence, less injury to the fruit in handling.

It may also be applied to the purpose of family buildings, inside and out; and also lathing and plastering, with much utility, as it may be readily moved about the room for the purposes mentioned; and also for outside work in building, as it need not take up but little room, it being made portable and adjustable.

Claim.

What I claim as my improvement, and desire to secure by Letters Patent, is—

The notched standards E and braces H and I, in combination with the platform A, guards B, guides F, and keys G, arranged essentially as and for the purpose set forth.

ANDREW J. WRIGHT.
